ENGINE STARTER

Julius H. Bolles, John E. Antonidis, and Robert M. Critchfield, Anderson, Ind., assignors to General Motors Corporation, Detroit, Mich., a corporation of Delaware

Application February 13, 1946, Serial No. 647,388

14 Claims. (Cl. 74—6)

1

This invention relates to apparatus for starting an internal combustion engine, and particularly an airplane engine.

An object of the invention is to provide a starter unit adapted to be mounted on the accessory gear housing of the engine and having a pinion for engagement with one of the accessory driving gears operated by the engine and having means for excluding entrance of foreign matter into the housing while providing for the shifting of the pinion by means located outside the housing. In the disclosed embodiment of the invention, this object is accomplished by the combination with the accessory housing having an opening through which the pinion and the mechanism connecting it with the starting motor shaft is passed when the starter unit is assembled with the housing, of a plate provided by the starter unit for supporting the starting motor and for covering the opening in the housing to which the plate is secured, a support for the pinion carried by the engine frame to which the housing is attached, and means for shifting the pinion and including a cylindrical member extending through the plate and a lever supported by the motor for operating the cylindrical member and for controlling the motor switch.

Further objects and advantages of the present invention will be apparent from the following description, reference being had to the accompanying drawings, wherein a preferred embodiment of the present invention is clearly shown.

In the drawings:

Figs. 1 and 2 are side and end views, respectively, of an engine starter embodying the present invention.

Fig. 3 is a longitudinal, sectional view of the engine starter and a portion of the flywheel housing to which the engine starter frame is attached, taken on line 3—3 of Fig. 2.

Fig. 4 is a sectional view on line 4—4 of Fig. 3.

Fig. 5 is a fragmentary view showing how it is possible to close the starting motor switch in case of abutment of the pinion teeth with the flywheel gear teeth.

Fig. 6 is a view similar to Fig. 4, showing the pinion in mesh with the flywheel gear.

Fig. 7 is a longitudinal, sectional view of the starter switch taken on line 7—7 on Fig. 2.

Fig. 8 is a section showing a modified arrangement of the clutch housing and gear supported thereby.

The starting motor comprises a field frame 10 and bearing plates 11 and 12 providing bearings 13 and 14, respectively, for supporting an arma-

2

ture shaft 15 carrying an armature 16 and a commutator 17. The brushes which bear on the commutator and the field coils and pole pieces which are located around the armature are not shown, but it will be understood that these are connected in series and that one end of the series connection is grounded on the frame and the other is connected with a switch contact 20, Fig. 7, mounted on the frame 10. A switch housing 21, secured to the frame, insulatingly supports the other switch contact and terminal member 22 to which a wire is connected leading to a storage battery. The movable switch contact 23 is insulatingly supported by a rod 24 attached to a push button 25 guided by the switch housing 21. A spring 26 locates the contact 23 normally out of engagement with the contacts 20 and 22. The switch is actuated by a lever 26 pivoted upon a screw 27 fastened to the frame 10 and carrying an adjustable screw 28 secured by a lock nut 29. The head of screw 28 is so located as to engage the switch button 25 when the lever is moved to the position 26', Figs. 5 and 7. Lever 26 is actuated by a rod, not shown, connectable with the lever 26 through a hole 30 therein, said rod terminating in a handle or pedal (not shown) conveniently located for operation by the driver of the vehicle. It will be understood that the specific form of switch is not material and that disclosed is merely a suitable example.

The armature shaft 15 passes through a shaft seal 31 provided by the plate 12 and is connected with a gear 32 meshing with a gear 33 whose hub provides the cam member 34 of a one-way clutch. Gear 32 is attached to shaft 15 by a key 32a and is retained by a nut 32b. Member 34 provides notches 35 receiving clutch rollers 36 located between surfaces 37 of the notches 35 and a cylindrical clutch-driven member 38. The rollers 36 are urged into the narrower parts of the notches 35 by springs 39 which maintain plungers 40 in engagement with the rollers 36. The parts of the clutch are maintained in assembled relation by plates 41 and 42 attached by screws 43 to the member 34 and by a ring 44 permanently attached to the member 34 and having a central opening in alignment with a hole 45 in plate 12, through which the tubular extension 46 of the driven clutch member 38 extends.

Clutch member 38 is permanently attached to a pinion 50 which meshes with a gear 51 connected with the engine to be started, the hub 52 of pinion 50 being permanently brazed to the part 38. Hub 52 carries bearing bushings 53 which are slidably along a rod or stub shaft 54

fixed to the engine frame F to which an accessory gear housing 55 is attached. Shaft 54 is located in alignment with a cylindrical bore 56 of the housing 55 which receives and locates a cylindrical flange 57 provided by the plate 12 which is attached to the accessory housing 55 by screws 58. Thus the accessory housing 55 supports the plate 12 and the electric starting motor; and the engine frame F supports the pinion 50 and the mechanism for connecting it with the motor shaft gear 32.

The tubular extension or sleeve 46 of the driven clutch member 38 houses cups 60 and 61. Discs 62 and 63 are located and spaced by a snap ring 64 and springs 66 and 67 confined under compression, respectively, by the cup 60 and disc 62 and by the disc 63 and cup 61, said cup 60 being retained by a snap ring 68.

The function of spring 67 is to demesh the pinion 50 from gear 51 and to maintain the pinion in the demeshed position shown in Fig. 3. The function of spring 66 is to permit closing of the starter switch in case the teeth of the pinion 50 abut end-to-end on the teeth of the gear 51. When gear tooth abutment occurs in the attempt to mesh the pinion with the gear by movement of the lever 26 toward position 26' (Fig. 5), motion of the sleeve 46 will be arrested but the lever 26 can be moved into position for closing the starter switch since the cup 60 can travel toward the right and compress the spring 66, as shown in Fig. 5. The motor will operate to turn the pinion to relieve gear tooth abutment. As soon as gear tooth abutment is relieved, the pinion 50 will be moved quickly by the spring 66 into full engagement with the gear 51, as shown in Fig. 6. During this movement, the gear 33 moves axially along the gear 32 while remaining in mesh therewith and spring 67 is compressed while spring 66 expands, spring 66 being stronger than spring 67. When the engine becomes self-operative, and tends to rotate the pinion 50 faster than it can be rotated by the electric motor, the clutch member 38 will override the clutch member 34. When the starting operation is completed, the driver releases the lever 30 so that spring 67 is free to demesh the pinion 50 and return the parts to their normal positions shown in Fig. 3.

As stated before, the bore 56 of the housing 55 is located concentrically with respect to the rod 54. The flange 57 and the hole 45 in the plate 12 are in concentric relation. Therefore, the hole 45 will be concentric with the rod 54. Sleeve 46 of the clutch part 38 being concentric with the pinion bearings 53, will be concentric with the hole 45. Hole 45 is slightly larger than sleeve 46 and entrance of dirt around the sleeve 46 into the housing 55 is prevented by a leather washer 70 attached to plate 12 bearing against the sleeve 46. Spring 67 urges the ring 44 against the washer 70, hence the latter serves as a brake to bring the pinion 50 quickly to a stop after the lever 26 is released. In the demeshed position of the pinion 50 there is clearance between hub 52 and left bearing bushing 53 of pinion 50 and cup 61 so that spring 67 is effective to urge plate 44 against washer 70 and the latter against the plate 12.

In the arrangement shown in Fig. 8, the gear 33 is not positioned on the outer periphery of the driving member of the clutch as in Fig. 3, but instead, the ring 44 which is permanently attached to the driven member 34 has a hub 75 projecting therefrom and surrounding the sleeve 76

46. The gear 33 is brazed or otherwise secured to this hub and is adapted to mesh with and be driven by the pinion 32 just as in the device disclosed in Fig. 3.

5 While the embodiment of the present invention as herein disclosed, constitutes a preferred form, it is to be understood that other forms might be adopted, all coming within the scope of the claims which follow:

What is claimed is as follows:

1. Engine starting apparatus comprising the combination of a housing having an opening, a plate attached to the housing and covering the opening, an electric motor supported by the plate and having an armature shaft, a gear fixed to the armature shaft, a rod within the housing parallel to the armature shaft, means slidably supported by the rod for connecting the armature shaft gear with the engine to be started and including a gear meshing with the armature shaft gear and a pinion connected with the second gear and axially movable into mesh with a gear in the housing connected with the engine, a tubular, pinion-shifting member extending from the hub of the pinion through an opening in the plate in alignment with the rod and providing on its interior two spring abutments intermediate its ends, one facing the rod and the other away from the rod toward the outer end of the member, a spring located between the rod and the abutment facing the rod for demeshing the pinion, an element slidable within the member at the end thereof remote from the pinion, a spring located between the element and the second mentioned abutment, a motor control switch, and means for operating the switch and the element whereby, in case of arresting movement of the member due to gear tooth abutment, the second spring will yield to permit closing the motor switch.

2. Engine starting apparatus comprising the combination of a housing having an opening, a plate attached to the housing and covering the opening, an electric motor supported by the plate and having an armature shaft, a gear fixed to the armature shaft, a rod within the housing parallel to the armature shaft, means slidably supported by the rod for connecting the armature shaft gear with the engine to be started and including a pinion journaled on the rod, an overrunning clutch driven-part attached to the pinion, an overrunning clutch driving-part surrounding the driven part, and a gear attached to the driving-part and meshing with the armature shaft gear, a pinion shifting member extending from the driven-part of the clutch through an opening in the plate to the exterior of the housing, a motor control switch, and means for operating the member and the switch.

3. Engine starting apparatus comprising the combination of a housing having an opening, a plate attached to the housing and covering the opening, an electric motor supported by the plate and having an armature shaft, a gear fixed to the armature shaft, a rod within the housing parallel to the armature shaft, means slidably supported by the rod for connecting the armature shaft gear with the engine to be started and including a pinion journaled on the rod, an overrunning clutch driven-part attached to the pinion, an overrunning clutch driving-part surrounding the driven-part, and a gear attached to the driving-part and meshing with the armature shaft gear, a tubular pinion shifting member extending from the driven-part of the clutch through an opening in

the plate in alignment with the rod to the exterior of the housing, said member providing a spring engaging abutment on its interior, a spring located between the rod and the abutment for demeshing the pinion, a motor control switch, and means for operating the member and the switch.

4. Engine starting apparatus comprising the combination of a housing having an opening, a plate attached to the housing and covering the opening, an electric motor supported by the plate and having an armature shaft, a gear fixed to the armature shaft, a rod within the housing parallel to the armature shaft, means slidably supported by the rod for connecting the armature shaft gear with the engine to be started and including a pinion journaled on the rod, an overrunning clutch driven-part attached to the pinion, an overrunning clutch driving-part surrounding the driven-part, and a gear attached to the driving-part and meshing with the armature shaft gear, a tubular pinion shifting member extending from the driven-part of the clutch through an opening in the plate in alignment with the rod to the exterior of the housing, said member providing on its interior two spring abutments intermediate its ends, one facing the rod and the other away from the rod toward the outer end of the member, a spring located between the rod and the abutment facing the rod for demeshing the pinion, an element slidable within the member at the end thereof remote from the pinion, a spring located between the element and the second mentioned abutment, a motor control switch, and means for operating the switch and the element whereby, in case of arresting movement of the member due to gear tooth abutment, the second spring will yield to permit closing the motor switch.

5. Engine starting apparatus comprising the combination of a housing having an opening, a plate attached to the housing and covering the opening, an electric motor supported by the plate and having an armature shaft, a gear fixed to the armature shaft, a rod within the housing parallel to the armature shaft, means slidably supported by the rod for connecting the armature shaft gear with the engine to be started and including a pinion journaled on the rod, an overrunning clutch driven-part attached to the pinion, an overrunning clutch driving-part surrounding the driven-part, and a gear attached to the driving-part and meshing with the armature shaft gear, a tubular pinion shifting member extending from the driven-part of the clutch through an opening in the plate in alignment with the rod to the exterior of the housing, said member having intermediate its ends an internal annular groove, a snap ring received by the groove and providing two abutments, two discs within the member and respectively in engagement with the abutments, two cup-elements within the member at opposite ends thereof, two helical springs within the member and located, respectively, each between a disc and a cup-element, the rod retaining the cup-element adjacent thereto, means at the outer end of the member for retaining the other cup-element, a motor control switch, and means for operating the switch and the element whereby, in case of arresting movement of the member due to gear tooth abutment, the second spring will yield to permit closing the motor switch.

6. Engine starting apparatus comprising the combination of a housing having an opening, a plate attached to the housing and covering the

opening, an electric motor supported by the plate and having an armature shaft, a gear fixed to the armature shaft, a rod within the housing parallel to the armature shaft, a pinion slidable upon the rod into mesh with a gear of the engine to be started, a tubular member supported by the pinion in axial alignment therewith, said plate having an opening in alignment with the rod through which the tubular member extends, means movable with the member for connecting the tubular member with the armature shaft gear, a washer attached to the plate and located between the plate and said means and engageable with said member to exclude entrance of dirt into the housing and serving as a brake when engaged by said means, a spring located within the member and applying between the rod and the member a force for demeshing the pinion and for causing said means to engage the washer, a motor control switch, and means for operating the switch and the member.

7. An engine starter drive for use with an electric motor having an armature shaft and a gear supported thereby and for use with an engine having a gear connected with its crank shaft and a rod located parallel to the axis of the gear, said drive comprising the combination of a pinion slidable on said rod into and out of mesh with the engine gear, a tubular member attached to the pinion and surrounding the rod and adapted to receive the application of a pinion meshing force, a spring within the member and adapted to exert a force between the member and rod to demesh the pinion, and means supported by the member for transmitting motion from the electric motor to the pinion, said means including a gear meshing with the armature shaft gear and an overrunning clutch between said gear and pinion.

8. An engine starter drive for use with an electric motor having an armature shaft and a gear supported thereby and for use with an engine having a gear connected with its crank shaft and a rod located parallel to the axis of the gear, said drive comprising the combination of a pinion slidable on said rod into and out of mesh with the engine gear, a tubular member attached to the pinion and surrounding the rod and adapted to receive the application of a pinion meshing force, a spring within the member and adapted to exert a force between the member and rod to demesh the pinion, and means supported by the member for transmitting motion from the electric motor to the pinion and including a one-way clutch driven member provided by the tubular member, a one-way clutch driving member surrounding the driven member and supported by the tubular member and a gear meshing with the armature shaft gear and surrounding the clutch driving member and attached thereto.

9. An engine starter drive for use with an electric motor having an armature shaft and a gear supported thereby and for use with an engine having a gear connected with its crank shaft and a rod located parallel to the axis of the gear, said drive comprising the combination of a pinion slidable on said rod into and out of mesh with the engine gear, a tubular member attached to the pinion and surrounding the rod, a spring within the member and adapted to exert a force between the member and rod to demesh the pinion, means supported by the member at the end portion thereof remote from the pinion for transmitting a pinion-meshing force yieldingly to the member, and means supported by the member for transmitting motion from the elec-

tric motor to the pinion and including a gear meshing with the armature shaft gear.

10. An engine starter drive for use with an electric motor having an armature shaft and a gear supported thereby and for use with an engine having a gear connected with its crank shaft and a rod located parallel to the axis of the gear, said drive comprising the combination of a pinion slidable on said rod into and out of mesh with the engine gear, a tubular member attached to the pinion and surrounding the rod, a spring abutment part within the tubular member intermediate its ends, two spring retaining cups respectively located within the tubular member on opposite sides of the abutment part, said cups being normally located respectively adjacent the pinion and at the end of the tubular member remote from the pinion, two helical springs located respectively between the cups and the spring abutment, the pinion providing a retainer for the cup adjacent thereto and said cup being adapted to engage the rod, means provided by the tubular member for retaining the other cup within it, said other cup being adapted to receive the application of a force which is transmitted through the associated spring to the tubular member to mesh the pinion with the engine gear, the other spring being adapted to apply a force between the rod and the member to demesh the pinion, and means supported by the member for transmitting motion from the electric motor to the pinion and including a gear meshing with the armature shaft gear.

11. Engine starting apparatus comprising the combination of a housing having an opening, a plate attached to the housing and covering the opening, an electric motor supported by the plate and having an armature shaft, a gear fixed to the armature shaft, a rod within the housing parallel to the armature shaft, means slidably supported by the rod for connecting the armature shaft gear with the engine to be started and including a pinion journaled on the rod, an overrunning clutch driven-part attached to the pinion, an overrunning clutch driving-part surrounding the driven-part, an annular gear mounted on the periphery of the driving-part and meshing with the armature shaft gear, a pinion shifting member extending from the driven-part of the clutch through an opening in the plate to the exterior of the housing, a motor control switch, and means for operating the member and the switch.

12. Engine starting apparatus comprising the combination of a housing having an opening, a plate attached to the housing and covering the opening, an electric motor supported by the plate and having an armature shaft, a gear fixed to the armature shaft, a rod within the housing parallel to the armature shaft, means slidably supported by the rod for connecting the armature shaft gear with the engine to be started and including a pinion journaled on the rod, an overrunning clutch comprising a driven-part attached

5 to the pinion and a cup-shaped driving-part surrounding the driven-part and having a hub projecting from the face thereof, an annular gear secured to said hub and meshing with the armature shaft gear, a pinion shifting member extending from the driven-part of the clutch through an opening in the plate to the exterior of the housing, a motor control switch, and means for operating the member and the switch.

10 13. Engine starting apparatus comprising a housing having an opening, a plate secured to the housing and covering said opening, a starting motor supported by the plate, said motor having an armature shaft carrying a driving gear, a gear positioned in the housing, said gear being connected with the engine and adapted to be operated by the starting motor to start said engine, a rod in the housing parallel to the armature shaft, means slidable on said rod for connecting

15 the driving gear with the engine gear including a gear engaging said driving gear, a pinion movable into engagement with the engine gear and an overrunning clutch between said gear and pinion, a member extending through an opening in the supporting plate for shifting said slidable

20 means to effect engagement of the pinion and engine gear, a motor control switch and means for operating said member and said switch.

14. Engine starting apparatus comprising a housing having an opening, a plate secured to the housing and covering said opening, a starting motor supported by the plate, said motor having an armature shaft carrying a driving gear, a gear positioned in the housing, said gear being connected with the engine and adapted to be operated by the starting motor to start said engine, a rod in the housing parallel to the armature shaft, means slidable on said rod for connecting the driving gear with the engine gear including

25 a gear engaging said driving gear, a pinion movable into engagement with the engine gear and an overrunning clutch between said gear and pinion, a member extending through an opening in the supporting plate for shifting said slidable

30 means to effect engagement of the pinion and engine gear, a motor control switch and means for operating said member and said switch.

14. Engine starting apparatus comprising a housing having an opening, a plate secured to the housing and covering said opening, a starting motor supported by the plate, said motor having an armature shaft carrying a driving gear, a gear positioned in the housing, said gear being connected with the engine and adapted to be operated by the starting motor to start said engine, a rod in the housing parallel to the armature shaft, means slidable on said rod for connecting the driving gear with the engine gear including

35 a gear engaging said driving gear, a pinion movable into engagement with the engine gear and an overrunning clutch between said gear and pinion, a member extending through an opening in the supporting plate for shifting said slidable

40 means to effect engagement of the pinion and engine gear, a motor control switch and means for operating said member and said switch.

14. Engine starting apparatus comprising a housing having an opening, a plate secured to the housing and covering said opening, a starting motor supported by the plate, said motor having an armature shaft carrying a driving gear, a gear positioned in the housing, said gear being connected with the engine and adapted to be operated by the starting motor to start said engine, a rod in the housing parallel to the armature shaft, means slidable on said rod for connecting the driving gear with the engine gear including

45 a gear engaging said driving gear, a pinion movable into engagement with the engine gear and an overrunning clutch between said gear and pinion, a member extending through an opening in the supporting plate for shifting said slidable

50 means to effect engagement of the pinion and engine gear, a motor control switch and means for operating said member and said switch.
